UNITED STATES PATENT OFFICE.

FRED HOLMES REES, OF ELMIRA, NEW YORK.

STATION-INDICATOR.

SPECIFICATION forming part of Letters Patent No. 629,605, dated July 25, 1899.

Application filed March 23, 1899. Serial No. 710,239. (No model.)

To all whom it may concern:

Be it known that I, FRED HOLMES REES, a resident of Elmira, in the county of Chemung and State of New York, have invented certain new and useful Improvements in Station-Indicators; and I do hereby declare the following to be a full, clear, and exact description of the invention, such as will enable others skilled in the art to which it pertains to make and use the same.

The invention relates to indicators, and has for its object to provide a simple, economical, and effective station-indicator.

The invention consists in the construction hereinafter described and pointed out.

In the accompanying drawings, Figure 1 is a broken front elevation. Fig. 2 is an end elevation of the mechanism removed from its case. Fig. 3 is an opposite end elevation of the same. Fig. 4 is an enlarged elevation of a star-wheel, spring-detent, and bell. Fig. 5 is a similar view of a modification. Fig. 6 is a partial elevation of a roller and gear connected by a spring. Fig. 7 is a transverse section showing the same, and Fig. 8 is an end elevation of two rollers driven by a sprocket chain.

Numerals 1 denote a case conveniently made of wood and having an opening or window 2, preferably glazed, to render visible the particular indications—as, for example, the names of stations, streets, or the like—displayed behind it by the operation of the mechanism to be described.

33 indicate frames made of brass, iron, or any suitable material and removably secured in the case by means of screws 4 or other suitable fastenings. Preferably these frames are made separate and provided with feet 5 to receive the screws or other fastening devices, which should be of such character and number as to hold the frame or frames securely. In the frames are journaled two rollers 6 and 7, having fixed at their ends gears 8 and 9, respectively. An intermediate gear is denoted by 10, which meshes with both gears 8 and 9.

11 denotes a handle fixed to the axis of roller 8, in the present instance suitably prolonged beyond its bearing in the frame and extended to the exterior of the case.

12 denotes a band, preferably of black material, provided with white indicators, or vice

versa, and having its ends wrapped about the rollers in opposite directions, so that as it is wound on a roller by its rotation the band 55 is unwound from the other, the rollers being connected by the gears to move in unison and in either direction. Obviously the rollers could be thus moved by sprockets and chain. The band being provided with a series of 60 names or the like suitably arranged thereon, the rollers can be manipulated at will to display all or any part of the series of names in succession and by reversing the rollers display the same names in reverse order, as heretofore practiced.

13 denotes a brass star-wheel suitably fixed on the axis of one of the rollers extended through its bearing in the frame. This wheel may be situated either on the inside or on the 70 outside of the case. It is combined with a spring 14, fixed in the present instance to the interior of the case. The spring is curved or bent, as indicated at 15, to stop the wheel, but so as to permit said wheel to be turned in 75 either direction when sufficient force is applied to overcome the tension of the spring. By preference the spring has an extension 16, situated near a bell 18 and combined with a spring-actuated hammer, so that when the 80 star-wheel is turned and the spring 14 thereby put under tension the hammer-spring is also put under tension, so that the hammer may cause the bell to ring when the hammer-supporting spring is released.

85 The star-wheel is arranged to be moved the distance of one tooth and the band the distance between two names thereon simultaneously, and the spring in co-operation with the wheel stops the band accurately and in proper 90 relation to the display-opening and simultaneously sounds the bell.

19 denotes a spring which carries the bell-hammer 18', and 20 denotes a weak spring attached to the hammer and situated in the 95 path of the extension 16 of spring 14. In operation the latter spring every time a tooth of the star-wheel passes over the part 15 out of one interdental space to another bends spring 20 and passes it twice, returning to its 100 normal situation. In the first stroke of the spring extension 16 it carries the spring 20 against the hammer extension 20', which sustains spring 20, so that the hammer is moved

from the bell and the spring 19 put under tension. The hammer having been sufficiently moved in manner indicated, the spring extension 16 escapes from the end of spring 20 and permits spring 19 to sound the bell. The spring extension in returning easily moves aside the spring 20, having no subsidiary support on its face opposite the hammer extension 20'. In some cases it is contemplated fixing the hammer 21 directly to spring extension 16 by a weak spring 22. The hammer and spring are so combined with a stop 23 as to temporarily arrest a weak spring 22, carried by extension 16, until it is sufficiently bent to escape said stop, whereupon the bell is sounded.

Preferably brass will be used for the wheels and frame or frames; but any suitable material may be employed. The frames are made easily attachable to and detachable from the case to provide for convenient assemblage, substitution, removal, or repairs of parts. The spring is made to do double duty, being adapted to act as a stop and prevent overrunning and to sound the bell.

The construction intermediate the roller and bell, including the main spring and the hammer, is simplified as compared with prior devices of the same general character.

30 The bell is preferably put on the inside of the case to avoid the notice of meddlers and for its general protection, and the case may be provided with openings for escape of sound.

I am aware that a bell has been used with 35 a roller-carried band, and my improvement in this particular consists in the simplified and improved construction hereinafter pointed out.

As the display-band becomes more or less 40 wound upon one of the rollers in the operation of the device, it is evident that a continued operation will result in either a very loose condition of the band or it will be drawn so tightly as to tear or break. Therefore some 45 means must be provided to permit one roll to adjust its movement to compensate for the condition of the band, or, in other words, to keep it sufficiently taut for successful operation. In Figs. 6 and 7 I have illustrated my preferred construction for accomplishing this 50 result. A spirally-arranged spring 21 is secured at one end to the roller, as 6, and at the other end to the gear-wheel, as 8, the latter being loose upon its shaft. The roller 55 will thus be permitted to revolve more or less rapidly than the gear-wheel, the spring being of sufficient tension to keep the display-band taut at all times.

Having thus described my invention, I 60 claim—

1. In a station-indicator or the like, a combination of the case, an alarm within the case, band-carrying rollers, a star-wheel fixed on the axis of one of the rollers, and means for 65 temporarily locking the star-wheel, said means being also adapted to sound the alarm.

2. In a station-indicator or the like, the combination of the case, an alarm within the case, the rollers geared to rotate, the display-band, the star-wheel fixed on the axis of one of the 70 rollers, and the spring adapted to stop the star-wheel and temporarily lock the rollers, said spring also sounding the alarm.

3. In a station-indicator or the like, the combination of the case, an alarm secured within 75 the case, a frame detachably fixed in the case, the rollers mounted in said frame and geared to rotate, the display-band operated by movement of the rollers, the star-wheel fixed on the axis of one of the rollers, and the spring 80 adapted to stop the wheel and temporarily lock the rollers, said spring also sounding the alarm.

4. In a station-indicator or the like, the combination of the band-carrying rollers, the star-wheel fixed on the axis of one of the rollers, the spring engaging the star-wheel to temporarily lock the rollers in a situation to properly set the display-band, and a bell, said spring having an extension situated near the 90 bell to ring the same when the spring is actuated by a movement of the star-wheel.

5. In a station-indicator or the like, the combination of a perforated case, a bell within the case, band-carrying rollers geared to rotate, a star-wheel fixed on the axis of one of the rollers, and a spring engaging the star-wheel and temporarily locking the rollers, said spring also sounding the bell. 95

6. In a station-indicator or the like, the combination of a case, a bell within the case, a bell-hammer to sound the bell, band-carrying rollers, a star-wheel fixed to one of the rollers, and a spring-detent to engage the star-wheel and temporarily lock the rollers in 100 a situation to properly set the display-band, said spring having an extension to actuate the bell-hammer.

7. In a station-indicator or the like the combination of a bell, a bell-hammer, the band-carrying rollers, a star-wheel fixed to one of the rollers, a spring-detent, said spring having an extension to actuate the hammer, and a subsidiary spring intermediate the detent-spring and the hammer said subsidiary spring 115 having a support adjacent one of its faces to defend it against the detent-spring extension.

8. In a station-indicator or the like, the combination of a case, a bell within the case, band-carrying rollers, a star-wheel fixed to one of the 120 rollers, and a spring-detent adapted to engage the star-wheel and temporarily lock the rollers in a situation to properly set the star-wheel, said spring having an extension carrying a hammer to sound the bell. 125

In testimony whereof I have signed this specification in the presence of two subscribing witnesses.
